CLAIM

The ornamental design for a motor vehicle jack, substantially as shown and described.

DESCRIPTION

FIG. 1 is a side elevational view of a motor vehicle jack showing my new design, the opposite side being substantially a mirror image thereof;

FIG. 2 is a left end elevational view thereof;

FIG. 3 is a right end elevational view thereof; and
FIG. 4 is a sectional view taken along line 4—4 in FIG.

1.

FIG. 3
